ATTORNEY

Patented June 26, 1945

Des. 141,705

UNITED STATES PATENT OFFICE

141,705

DESIGN FOR A GLIDER SWING

John R. Slaughter, Dallas, Tex.

Application April 21, 1945, Serial No. 119,122

Term of patent 14 years

(Cl. D15—11)

To all whom it may concern:

Be it known that I, John R. Slaughter, a citizen of the United States, residing at Dallas, in the county of Dallas and State of Texas, have invented a new, original, and ornamental Design for a Glider Swing, of which the following is a specification, reference being had to the accompanying drawing, forming part thereof.

Figure 1 is a perspective view of a Glider Swing showing my new design.

Figure 2 is a front elevational view, and
Figure 3 is an end elevational view.

I claim:

The ornamental design for a glider swing, as shown.

JOHN R. SLAUGHTER.
